DES 46

FIG. 1

3-14-1844

Design.

FIG. 11

Design

H. BIGGINS NEW YORK

SPITTOON

Des. 46

Henry Biggins, New York City
Letters Patent (Design No 46) dated 14th March 1846.

The Schedule referred to in these Letters Patent and
making part of the same

To all whom it may concern-

Be it known that I, Henry
Biggins of the City County and State of New York have invented
and produced a new Design for a "Spittoon" made of cast iron

Des. 46

and I do hereby declare that the following is a full and exact description of the same, reference being had to the annexed drawings, making a part of this Specification in which figure I is a plan or top view of the cover of the "Spittoon" and figure II is a plan or top view of the bottom or retaining reservoir raised upon its foot.

Figure I, is in the form of a shell and has an opening near its centre, through which fluids and other substances that will by their own gravity descend on an inclined surface and fall into the cup or cavity figure II where they are retained, to be removed at pleasure. Figure II is a bowl cup or cavity so formed as to fit or match with the under side of the shell or cover figure I, and sustains it in an elevated position, thereby furnishing a reservoir for the reception of such fluids or other substances as it may be designed. This reservoir or cavity will be known as A. fig. II in the drawings, and is raised by placing under it three feet or legs made in the form of dolphins' heads, and are designated in the drawings by b, b, b. the whole forming one piece of casting.

I combine these two pieces, figures I, and II, in completing the "Spittoon," by simply placing the cover (or figure I.) upon the top of fig II, thereby forming an ornamental metal box or "Spittoon."

I further ornament my "Spittoon" by bronzing, or Japaning, at discretion, or not.

What I claim, as my invention or production, is the casting in iron ornamented as above described, a "Spittoon" or "Spit box".
